MEANS AND METHOD OF TUBULATING LAMP BULBS

Filed Aug. 6, 1925

UNITED STATES PATENT OFFICE

JOHN S. VAN HORNE, OF FRANKLIN, OHIO, ASSIGNOR TO VAN HORNE TUBE COMPANY,
OF FRANKLIN, OHIO, A CORPORATION OF OHIO

MEANS AND METHOD OF TUBULATING LAMP BULBS

Application filed August 6, 1925. Serial No. 48,493.

My invention relates to the manufacture of radio detector and amplifying tubes, incandescent lamp bulbs and the like and more particularly to such tubes and bulbs of the 5 tipless type, wherein the bulb or tube is exhausted through its bottom. The invention pertain more especially to means and method of tubulating such bulbs with view to facilitating manufacture and minimizing break- 10 age.

Such radio tubes and lamp bulbs as usually manufactured are provided with an inwardly extending tubular glass mount for the filament and element support, which mount is attached by fusing to the bottom or base of the 15 bulb. This mount usually comprises a short glass tube flared at its lower end into conformity with the base of the bulb and has its upper end pinched or compressed while at 20 fusing temperature upon the lead wires, which extend through the tubular mount into the interior of the tube or bulb, and upon such filament and element supports as may be necessary. It is customary to provide with- 25 in the tubular mount, a tubulating stem or exhaust tube, which communicates with the interior of the bulb through an opening in the mount for the purpose of exhausting the bulb, and if so desired refilling it with an 30 inert gas. Such exhaust tube or tubular stem is attached interiorly of the hollow mount by fusing. Various methods have been proposed for insuring an open passage through 35 such tubulating stem to the interior of the bulb. One of the usual methods heretofore utilized is to fuse the tubulating stem to the interior of the hollow mount, and while the point of attachment is still at fusing temperature to direct a jet of compressed air through 40 the tubulating stem, thereby blowing a hole thru the wall of the mount from the bore of such tube or stem. Another proposed method is to insert the tubulating stem or exhaust tube prior to the compression or 45 pinching of the end of such mount, upon the lead wires and element support, thereby at the same time incorporating the tubulating stem or exhaust tube in the press. The end 50 of the tubulating stem or exhaust tube as well as the end of the mount being at fusing

temperature during this operation, the heat softened end of the tube will collapse and close the bore or passage. To prevent such collapse, short lengths of metal tubing forming non-yielding metallic bushings are permanently inserted in the ends of the exhaust tubes or tubulating stems. Such permanent bushings not only reduce the diameter of the bore or capacity of the tubulating stem, thereby necessitating the use of a larger tube, but 55 being unyielding they resist the contraction of the compressed ends of the mount in cooling, thereby subjecting the mount to undue 60 stresses and strains, which results in excessive breakage.

In the present invention there is contemplated the use of a tubulating stem or exhaust tube incorporated in the press of the mount by fusing, the bore or passage of which is maintained opened, and the collapse of the tube prevented during the pinching or compression of the mount while in a plastic state, by the temporary insertion of a removable resilient core, capable of yielding sufficiently to compensate for the contraction of the tube and mount when cooling, and which is capable of subsequent removal to afford a maximum opening through the tubulating stem. It has been found in practice that a suitable, convenient and economical form of removable resilient core consists of a helically wound wire, which being inserted in the end of the tubulating stem remains in place during the fusing operation and compression of the mount about the stem, after which such temporary core or bushing is readily removed by pulling upon the protruding end of the wire whereupon the coiled wire insert will elongate or unwind from within the tube, leaving the passage or bore of maximum diameter. While a helically wound wire has been found to be convenient and economical other forms of yielding, removable bushings or inserts may be utilized to accomplish the same end, and, therefore, the invention is 75 not limited to the specific form of insert.

The object of the invention is to simplify the means and mode of tubulating incandescent lamp bulbs, radio tubes and the like, whereby the methods of manufacture will 100

be facilitated and improved, and the amount of breakage minimized.

A further object of the invention is to provide means for preventing the collapse of the 5 tubulating stem or exhaust tube during the fusing operation, while insuring a passage or bore of maximum diameter leading through the stem into the bulb.

A further object of the invention is to provide 10 an insert or bushing to prevent the collapse of the tubulating stem or exhaust tube during the fusing operation, which will yield sufficiently to compensate for the shrinkage and contraction of the tube and mount during 15 cooling, thereby preventing undue stresses and strains within the mount and tube and minimizing breakage.

A further object of the invention is to provide 20 a removable insert or core, capable of resisting the compression of the mount and tube while in a fused condition, yet capable of being readily and easily removed from the tube after the latter has become hardened and cooled.

25 With the above primary and other incidental objects in view as will more fully appear in the specification, the invention consists of the features of construction, the parts and combinations thereof, and the mode of 30 operation or their equivalents as hereinafter set forth and described in the claims.

Referring to the accompanying drawings, wherein is shown the preferred, but obviously not necessarily the only forms of embodiment of the invention, Fig. 1 is a side elevation of a radio tube or bulb of the tipless type, illustrating the tubulating stem, communicating with the interior of the bulb, through the mount and sealed at its outer end. Fig. 2 is a perspective view of the mount and tubulating stem, attached thereto, illustrating the manner of removing the temporary resilient bushing or insert. Fig. 3 illustrates the manner of assembly of the parts in a tubulating machine, wherein the mount and tube are heated to fusing point and compressed. Fig. 4 is a detail view of the resilient temporary insert or core. Fig. 5 illustrates a modified form of stranded removable inserts 45 or cores. Fig. 6 is a detail perspective view of a further modification thereof.

Like parts are indicated by similar characters of reference throughout the several views.

55 While reference is made herein to incandescent lamp bulbs, and to radio detector and amplifying tubes, it is to be understood that the invention is not limited to either specific construction, but includes both, and also any 60 other form of vessel or container, to which an exhaust or filling tube is to be attached by fusing or any similar construction wherein a vent port is to be kept open by use of a removable insert or core, which will prevent 65 the closing or collapse of such vent port,

while the material is in a plastic condition.

In the accompanying drawings, 1 indicates a typical form of bulb or vessel, which is to be exhausted and if the occasion requires, refilled with an inert gas or the like. Projecting 70 inwardly from the base or bottom of the bulb 1, is the mount or press 2. This mount is formed from a short length of glass tube, which being heated to plastic condition is extended or flared at one end as at 3, to form 75 a closure head for the bulb or vessel 1. The inner end of the mount is pinched or compressed, while in a soft or plastic condition to embed therein a series of lead wires 5, necessary for the electrical connection of the elements to be inclosed within the bulb or vessel 1. Before pinching or compressing the softened end of the mount 2 upon the lead wires 5, a tubulating stem or exhaust tube 6 is inserted through the mount 2, to which it is attached by being embedded in the compressed terminal 4 of the mount. This operation is 80 performed in the usual tubulating machine upon the head of which the several parts are assembled, as shown in Fig. 3. The mount 2 is supported in inverted position upon the head 7 of the tubulating machine, with the tubulating stem or exhaust tube 6, centrally disposed therein, and the lead wires 5 arranged in spaced relation extending through the mount 2 and through the spacing, or locating holes in the head 7 of the tubulating machine. To prevent the collapse of the tubulating stem or exhaust tube 6, when the mount is subjected to compression, an insert 85 or core 8 is deposited in the end of the stem 6. This insert or core may be dropped through the tube 6 from its upper end, in the assembly, shown in Fig. 3, and is preferably received in a seat or depression in a head 7 of the tubulating machine so that in the finished product the extremity of the insert or core 8 may project beyond the extremity of the tube 6 and of the mount 2.

With the several parts assembled as in Fig. 3, the mount tube 2 which is inverted on the top of the head 7 of the tubulating machine is subjected to a blast jet flame which heats the lower end of the tube 2 forming the mount and the extremity of the tubulating stem 6, to a fusing or plastic condition. At this stage the parts are subjected to a pinching or compression operation, usually performed by automatic means which flattens the ends of the mount 2 into the press 4, serving to seal the lead wires 5 and tubulating stem 6, thereto. It is to prevent the collapse of the tube 6 or material reduction of the bore or passage therethrough during this pressing operation while plastic that the core or insert 8 is provided. Obviously, any core or bushing permanently sealed within the end of the exhaust tube will reduce the capacity of the tube. Moreover, a rigid or unyielding core or insert, will resist the shrinkage and contrac- 110 115 120 125 130

tion of the glass mount in cooling, resulting in the more or less breakage and setting up stresses and strains in the mount, which causes them to break at a later time upon slight concussion. In the present instance, uniformity of manufacture and elimination of breakage is achieved by making the insert core 8 of yielding or resilient character capable of being removed from the completed mount. To this end the insert or core is preferably a closely wound wire of helical formation, forming a tubular bushing similar to the commonly known helical spring. Such helically wound wire core or insert will yield or compress sufficiently to compensate for the shrinkage or contraction of the mount and tube, without subjecting such parts to breaking resistance. After the completion of the mount, the end of the insert may be grasped by a pair of pliers or other suitable instruments or tools, and by slight pull the core is elongated sufficiently to permit its easy removal from the tube. By subjecting such inserts or core to pulling strain, the successive turns of the helically wound wire are stretched into approximately their original straight strand formation, causing the successive turns to unwind within the end of the tube. A removal of the core or insert 8, by elongation, or unwinding it from within the tube, leaves the bore or passage entirely unobstructed and substantially equal to its original diameter.

While a soft wire wound to helical formation has been found to be quite efficient and the most convenient and simple form for present manufacturing process, it is to be understood that other material such as fiber might be employed in similar manner and also that the stranded insert or core might be made by other means than helical windings. For example, there has been illustrated in Fig. 5 a form of insert or core in which the strand is folded to and fro upon itself to parallelism to form a small yielding bundle of longitudinally disposed strand sections, which is insertable within the end of the exhaust tube and removable therefrom after the completion of the mount in the manner before described. That is to say, after the completion of the mount, the end of the folded strand being subjected to pulling tension, the successive sections of the strand will be unfolded and pulled from within the tube. In Fig. 6 there is shown a further adaptation, wherein a flat ribbon-like strand is shown folded to and fro upon itself in accordion fashion to form an insert or core, which is removable from the end of the tube by pulling in quite the same manner as that before described. Whatever the form of core may be, it will be noted that it is non-rigid and readily removable subsequent to the completion of the mount. By this means, manufacturing processes of tubulating incandescent lamps and radio tubes and

the like are greatly facilitated, enabling such operations to be performed rapidly and economically and with minimum breakage of the product.

While the insert or core may be made from various materials including some non-metallic substances as mentioned, the preferable material has been found to be nickel, or an alloy containing nickel.

Although the core or insert is preferably removed to afford a maximum capacity bore, such insert or core when of tubular form may, if desired, be left embedded in the end of the exhaust tube.

The term lamp bulb, and the like, as employed in the description and claims includes lightning arrestor vessels, mercury switch vessels and other vessels or containers in which reduced access openings are to be maintained, and those lamp bulbs, radio tubes and other vessels wherein the vessel is closed and element leads and the like sealed therein by pinching together the walls of the vessel while plastic, without the use of a separately formed "mount" which, when used, in effect comprises a wall for such vessels.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. In a construction of the character described, a mount, a tubulating stem fused thereto, and a yielding bushing having a passage communicating with the passage in said tube carried within said tube to prevent the collapse thereof during the fusing operation.

2. The combination with a lamp bulb or the like, and a mount connected therewith, and having lead wires extending through said mount, a tubulating stem sealed within said mount and a yieldable bushing within the tube at the region where it is so sealed to prevent the collapse thereof and to maintain communication with the interior of the bulb.

3. The combination with a lamp bulb or the like, of a mount carried thereby, a tubulating

- stem fused to said mount, and a yielding insert temporarily disposed in said tubulating stem at the region where it is fused to said mount to prevent the collapse of the tubulating 5 stem, and subsequently removed thereby insuring maintainance of communication between the stem and the interior of the bulb.
4. The combination with a tubular mount for a lamp bulb filament or the like, pinched 10 together at its end and lead wires extending through such pinched portion of the mount, of an exhaust tube also extending through the mount and fused to said mount at the pinched portion thereof, and a removable coiled wire 15 insert within the exhaust tube at such pinched portion to prevent collapse thereof during manufacture, and maintain an open passage through said tube.
5. The combination with a lamp bulb or the 20 like, of a tubulating tube fused thereto, and a yielding bushing carried within the tube during the fusing process to prevent collapse of the tube, and minimize breakage during the fusing operation.
- 25 6. The combination with a lamp bulb or the like, of a tubulating tube fused thereto, and a helically coiled wire bushing carried within the tube during the fusing operation to prevent collapse of the tube and minimize breakage.
- 30 7. The combination with a lamp bulb or the like, of a tubulating tube fused thereto, and a yielding metallic insert carried within the tube during the fusing operation to prevent 35 collapse of the tube and minimize breakage.
8. The combination with a lamp bulb or the like, of a tubulating tube fused thereto, and a helically wound wire bushing carried within the tube during the fusing operation to prevent 40 collapse of the tube, said bushing being subsequently removable by unwinding the wire from within the tube.
- 45 9. The combination with a lamp bulb or the like, of a tubulating tube fused thereto, and a strand of material bent upon itself to form a removable insert carried within the tube during the fusing operation to prevent collapse of said tube and subsequently removable therefrom by distention of said bent 50 strand into elongated formation.
- 55 10. The herein described method of tubulating lamp bulbs and the like consisting in inserting a removable body in the end of an exhaust tube to prevent collapse of the tube, fusing said tube to a filament mount, distorting the inserted body to make possible its removal from the tube, attaching the mount to the bulb, exhausting the bulb through said tube and sealing the tube.
- 60 11. The herein described method of tubulating lamp bulbs and the like, consisting in inserting a yielding body in the end of an exhaust tube, to prevent collapse of the tube and minimize breakage, fusing the tube carrying such insert to a filament mount, elongating 65

the yielding body to effect its removal to afford an open passage through the tube, attaching the mount to a bulb, exhausting the bulb through said tube and sealing the tube.

12. The herein described method of tubulating lamp bulbs and the like, consisting in inserting a helically wound wire in the end of a tube, to prevent collapse of the tube and minimize breakage during attachment, fusing the tube carrying such insert to a filament mount, unwinding the wire from the interior of the tube, attaching the mount to a bulb, exhausting the bulb through said tube, and sealing the tube.

13. The herein described method of tubulating lamp bulbs and the like, consisting in inserting a stranded body within the end of a tube to prevent collapse of the tube, fusing such tube to a mount, removing the inserted body by withdrawing the stranded body in an elongated form, attaching the mount to a bulb, exhausting the bulb through the tube and sealing the tube.

14. The herein described method of tubulating lamp bulbs and the like, consisting in inserting a resilient body in the end of a tube, to yieldingly resist collapse of the tube, fusing the tube to a mount, reducing the form of the resilient insert to make possible its removal from the tube to afford an unrestricted air 95 passage therethrough, attaching the mount to a bulb, exhausting the bulb through the tube and sealing the tube.

15. The herein described method of maintaining an open passage through a tubulating tube for lamp bulbs and the like during the process of fusing the tube to a bulb structure, consisting in inserting a removable core in said tube during the fusing operation and subsequently distorting the form of the core 100 to facilitate its removal and removing the core.

16. The herein described method of maintaining an open passage through a tubulating tube for lamp bulbs and the like during the process of fusing the tube to a bulb structure, consisting in temporarily inserting a resilient core in said tube during the fusing operation and subsequently removing the core.

17. The herein described method of maintaining an open passage through a tubulating tube for lamp bulbs and the like during the process of fusing the tube to a bulb structure, consisting in temporarily inserting a core comprising a helically wound strand in 120 said tube during the fusing operation and subsequently removing the core.

18. The herein described method of maintaining an open passage through a tubulating tube for lamp bulbs and the like during the process of fusing the tube to a bulb structure, consisting in temporarily inserting a removable core of stranded material in said tube, during the fusing operation and subsequently removing the core.

19. The herein described method of maintaining an open passage through a tubulating tube for lamp bulbs and the like during the process of fusing the tube to a bulb structure consisting in providing a removable core by forming a repetitious succession of convolutions in a continuous strand of material inserting such core in said tube during the fusing operation and subsequently removing the core.

20. The herein described method of tubulating lamp bulbs and the like wherein an exhaust tube is integrally united with a portion of the lamp bulb structure, including removably inserting a tubular nickel bushing within the end of the said tube to prevent its collapse during the process of its attachment.

21. The herein described method of tubulating lamp bulbs and the like, wherein an exhaust tube is integrally united with a portion of the lamp bulb structure, including inserting a tubular bushing formed from a nickel bearing alloy within the end of the said tube to prevent its collapse during the process of its attachment.

22. The herein described method of tubulating lamp bulbs and the like, wherein an exhaust tube is integrally united with a portion of the lamp bulb structure, including inserting a core formed from a nickel bearing metallic wire within the end of the said tube to prevent its collapse during the process of its attachment.

23. The herein described method of tubulating lamp bulbs and the like, wherein an exhaust tube is integrally united with a portion of the lamp bulb structure, including removably inserting a non-rigid core within the end of the said tube to prevent its collapse during the process of its attachment.

24. A filament mount, a tubulating tube affixed thereto by fusing, and resilient means carried within the tube to prevent collapse during the fusing operation.

25. The combination with a lamp bulb or the like, and a mount connected therewith, and having lead wires extending through said mount, a tubulating stem sealed within said mount and a resilient bushing within the tube at the region where it is so sealed to prevent the collapse thereof and to maintain communication with the interior of the bulb.

26. The herein described method of tubulating lamp bulbs and the like, wherein an exhaust tube is integrally united with a portion of the lamp bulb structure, including inserting a resilient core within the end of the said tube to prevent its collapse during the process of its attachment.

27. The method of maintaining an access opening in a vessel, including heating the vessel to a condition of plasticity, positioning a coiled wire insert core, compressing the

wall of the heated vessel thereabout while in a plastic state and subsequently removing the core.

28. The combination with a lamp bulb or the like of a tubulating tube fused thereto and a removable flexible insert carried within the tube to prevent collapse of the tube to insure an open passage therethrough.

29. A fusible vessel, a tubulating tube affixed thereto by fusing, and a resilient insert core located within the tube to prevent collapse during the fusing operation.

30. A fusible vessel, a tubulating tube affixed thereto by fusing, and a coiled wire insert core located within the tube to prevent collapse of the tube during the fusing operation.

31. A fusible vessel, a tubulating tube affixed thereto by fusing, and a longitudinally extensible insert core located within the tube to prevent collapse during the fusing operation.

In testimony whereof, I have hereunto set my hand this 28th day of July, A. D. 1925.

JOHN S. VAN HORNE.
